[57] CLAIM

The ornamental design for a machine for inverting a hay windrow, as shown and described.

DESCRIPTION

FIG. 1 is a front perspective of a machine for inverting a hay windrow, showing my new design;

FIG. 2 is a top perspective of the left hand side of FIG. 1;

FIG. 3 is a rear perspective of the right hand side of FIG. 1;

FIG. 4 is a rear perspective;

FIG. 5 is a front perspective of the right hand side of FIG. 1; and,

FIG. 6 is a front perspective of the left hand side of FIG. 1.

The forward end of the drawbar is shown in detail in FIGS. 2 and 5 but has been broken away in the remaining Figures for ease of illustration.
